UNITED STATES PATENT OFFICE

JOHN WIEDEMANN, OF CLEVELAND, OHIO, ASSIGNOR TO AMERICAN STOVE COMPANY,
OF ST. LOUIS, MISSOURI, A CORPORATION OF NEW JERSEY

DESIGN FOR A DINING CAR RANGE

Application filed May 5, 1931. Serial No. 39,720. Term of patent 14 years.

To all whom it may concern:

Be it known that I, JOHN WIEDEMANN, a citizen of the United States, residing in the city of Cleveland and State of Ohio, have invented a new, original, and ornamental Design for Dining Car Ranges, of which the following is a specification, reference being had therein to the accompanying drawing.

The accompanying drawing is a perspective view of the new dining car range, showing in my new design.

I claim:

The ornamental design for a dining car range as shown.

In testimony whereof, I hereunto affix my signature.

JOHN WIEDEMANN.
